Z. A. Carnes, by
G. C. Kennedy,
Attorney.

UNITED STATES PATENT OFFICE.

ZEN A. CARNES, OF WATERLOO, IOWA.

ROTARY VALVE FOR INTERNAL-COMBUSTION ENGINES.

Application filed January 7, 1922. Serial No. 527,725.

To all whom it may concern:

Be it known that I, ZEN A. CARNES, a citizen of the United States of America, and a resident of Waterloo, Blackhawk County, 5 Iowa, have invented certain new and useful Improvements in Rotary Valves for Internal-Combustion Engines, of which the following is a specification.

My invention relates to improvements in 10 rotary valves for internal combustion engines, and the object of my improvements is to provide a valve-casing in communication with an engine combustion-chamber, said casing containing a closed hollow rotatable 15 cylindric valve having separated independent passages isolated from the interior of the valve and adapted for alternate communications with said combustion chamber, and having an independent rotor therein for directly spraying a flowing cooling medium 20 along and in contact with the inner walls of the valve for cooling the bearing surfaces thereof.

This object I have accomplished by the 25 means which are hereinafter described and claimed, and which are illustrated in the accompanying drawings, in which Fig. 1 is an elevation of an internal combustion engine equipped with my said improved valve-casing and valve, with parts broken away. Fig. 2 is a view of the same, taken partly 30 in elevation and partly in longitudinal central section. Fig. 3 is a transverse section of said construction with parts broken away, and Fig. 4 is a transverse section on another 35 plane through said valve-casing and valve.

Similar numerals of reference denote corresponding parts throughout the several views.

40 The open end cylindrical valve-casing 1 has a water-jacket and is mounted on or annexed to the combustion-chamber 13 of an internal combustion engine 14, it being understood that the latter may be of any desired 45 type than that illustrated. The numeral 12 denotes a short curved pipe traversing the walls of said casing and combustion-chamber to effect communication therebetween and to serve alternately as hereinafter described, as an inlet- and an exhaust-passage. A closed end hollow cylindric rotatable valve 3 is mounted within and to fit the interior cylindrical hollow of said valve-casing. The numeral 2 denotes a pipe traversing the 55 walls of said valve-casing being also in com-

munication with a supply of a flowing cooling medium, such as cool water, and having its other end arranged for occasional communication with an inlet port or ports in one end of the valve 3. In the opposite end 60 of the cylindric wall of said valve may be provided one or more openings 8 for occasional communication with an opening into the valve-casing water-jacket, an outlet pipe 16 being in communication with the latter. 65 By this means, the circulation of cooling water or other liquid may be created longitudinally through the hollow of said valve. I have provided within the valve a rotor or vaned body 7—6 whose vanes extend into 70 the path of movement of a stream of liquid entering the valve from the pipe 2, the stream independently rotating said rotor, and the vanes of the rotor receiving the liquid and changing the direction of the latter to spray it upon the inner cylindric walls of the valve to said ports 8. The liquid thus is given a whirling movement and more effectively cools said cylindrical wall 75 and its bearing surface more evenly spread 80 throughout to reinforce the cooling action of the liquid in the water-jacket.

On a projecting end of the valve 3 is fixed a sprocket-wheel 4 carrying a sprocket-chain 5 and said chain and sprocket-wheel may be 85 carried and actuated by another sprocket-wheel not shown, driven by the engine or other means.

The valve 3 is traversed by two independent and separated cross-pipes 10 and 11, whose ends are sealed in the cylindric wall of the valve to isolate them from the hollow of the valve and said pipes cross each other at right angles obliquely longitudinally in such a manner that each pipe has one end 90 opening through the cylindric wall of the valve in the same transverse plane as the outer opening of the pipe 12 for alternate occasional communication therewith as said valve rotates. Longitudinally aligned spaced 95 inlet and exhaust ports 9 and 15 are provided in the walls of said valve-casing for occasional communications respectively with the other ends of the valve-pipes 10 and 11 as the valve rotates. It will be seen that this construction of the said coacting structures 100 permit the pipe 12 to be used alternately as an inlet and an exhaust pipe for the combustion chamber of the engine.

It is to be understood that modifications 110

in the illustrative structures herein are nevertheless within the principle of this invention and the scope of its protection.

Having described my invention, what I claim as new and desire to secure by Letters Patent, is:

1. The combination with the combustion chamber of an internal combustion engine, of a valve-casing having a water-jacket, 10 said casing having longitudinally spaced inlet and exhaust ports, and having in its opposite side a single port communicating with said combustion chamber, a hollow closed rotatable cylindric valve-body mounted and fitting within said valve-casing, said valve-body and said valve-casing having inlet and outlet ports at opposite ends thereof for effecting occasional registering communication between the valve-casing water-jacket 15 and the hollow of the valve-body, independent conduits crossing the hollow of the valve-body sealed therefrom and adapted to respectively alternately effect communication between said combustion chamber port 20 and the inlet and exhaust ports of said valve-casing when the valve-body is in rotation, and a vaned rotor mounted rotatably in the hollow of said valve-body to receive and be independently rotated by a fluid injected 25 through said inlet-ports of the valve-casing and valve-body, the entering fluid being diverted by said rotor to impinge upon the inner cylindric wall of the valve-body to flow thereover toward the outlet-ports of 30 the valve-body and valve-casing in a current circulating through the hollows of both said structures.

2. In combination, a valve-casing, a hollow closed cylindric valve rotatably mounted therein, said valve having an inlet-port at 40 one end for occasional communication with a source of liquid supply and having a discharge-port at its opposite end, independently rotatable radial vanes mounted in the valve adjacent said inlet-port to receive liquid therefrom and deflect it along the inner cylindric wall of the valve toward the discharge-port, and independent conduits traversing said valve uncommunicatingly for occasional communications with an 45 engine-port.

3. The combination with the combustion-chamber of an internal combustion engine, of a valve-casing having a common inlet- and exhaust-passage in communication with said combustion-chamber and also having spaced inlet- and exhaust-ports, a closed hollow rotary valve fitting said valve-casing having uncommunicating passages adapted to effect alternate communications when the 50 valve is rotated between said first-mentioned passage and said inlet- and exhaust-ports respectively only, and a vaned rotor independently rotatable within the hollow of said valve to be rotated by and cause an 55 initial spreading of a flowing cooling medium under head introduced within the valve over the inner wall thereof to cool the bearings of the valve when the valve is 60 in rotation.

Signed at Waterloo, Iowa, this 12th day of Dec., 1921.

ZEN A. CARNES.
